UNITED STATES PATENT OFFICE.

MARTIN L. RAHNER, OF PORTLAND, OREGON, ASSIGNOR TO OREGON BRASS WORKS, OF PORTLAND, OREGON.

BUBBLING DRINKING-CUP.

1,227,311.

Specification of Letters Patent.

Patented May 22, 1917.

Continuation in part of application Serial No. 785,221, filed August 18, 1913. This application filed January 18, 1915. Serial No. 2,806.

To all whom it may concern:

Be it known that I, MARTIN L. RAHNER, a citizen of the United States, residing in the city of Portland, county of Multnomah, and 5 State of Oregon, have invented certain new and useful Improvements in Bubbling Drinking-Cups, of which the following is a specification.

My invention relates to improvements in 10 bubbling drinking cups, and has among its salient objects,—to provide a simple and practical fountain drinking cup with means therein for receiving the force of the water discharged into the cup from the supply pipe 15 and directing it or checking its direction and force so that the main chamber of the cup must be first filled before the water can flow through the opening in its top, thereby equalizing the pressure and causing the 20 water to be discharged from the cup in a uniform manner and with little or no variation and with no "sputtering"; to provide a cup with a concaved upper surface, with non-squirt tubes extending from the concaved 25 top through the body of the cup and discharging into the drain below, thereby making it impossible for children to squirt water from the side of the cup by placing their hands over the cup, for the reason that 30 the water is forced through the non-squirt tubes and escapes below into the drain; to provide a simple and inaccessible (except by a screw-driver) means for regulating the discharge of the water into the cup.

35 Other advantages will be apparent from the following description of one practical embodiment of my invention, shown for illustrative purposes in the accompanying sheet of drawings,—in which—

40 Figure 1 is a vertical sectional elevation of a cup embodying my invention; and Fig. 2 is a top plan view thereof.

Some features of the present invention are 45 illustrated in my pending application, Serial No. 785,221, filed Aug. 18, 1913, and are now divided from that application. I refer particularly to the concaved top with the non-squirt tubes leading therefrom through the body of the cup to the drain below.

50 Referring now to the drawings in detail, the cup body comprises a lower portion 1, and an upper portion 2, secured together, as indicated. The upper portion 2 is provided with a concaved top 3, with a central open-

ing 4 from which the water is discharged in 55 bubbles. From said concaved top, two non-squirt tubes 5—5 extend through the body of the cup and discharge through the sides of the lower portion 1, as indicated. The lower portion 1 is threaded as at 6, whereby it can 60 be attached to any water supply pipe of the proper size, and has leading therethrough an inlet passageway 7, which is enlarged at its upper end and then is continued in a series of small inlet ports, as 8—8, discharging 65 into the main chamber of the cup above. 9 designates a valve member screwed into the lower portion of the body, substantially in the manner indicated, with its lower end adapted to seat upon the inlet opening 7 in a 70 way to close the same, or partially close it, as may be desired, when said valve member is screwed downwardly. Said member is provided around its upper portion with a flange or disk-like portion 10 which over- 75 lies the inlet ports 8—8, so that the water discharged through them into the main chamber of the cup first strikes said member and its force is checked and the chamber must be filled before the water will be 80 forced out of the discharge opening 4 in the concaved top. The upper end of said valve member is adapted, as at 11, to receive the end of a screw driver, with which it can be turned up or down, as desired, to regulate 85 the flow of the water into the cup.

Thus the force of the water discharged into the cup chamber is checked by the member 10 and makes it necessary for the cup to be filled before the water is discharged 90 through the discharge opening 4. This, in effect, constitutes a cushion for the water force from the supply pipe. Then again, the concaved top insures that there will be a thin sheet of water running over the top 95 surface of the cup and over the sides thereof, keeping the cup top clean.

I do not limit the invention to the particular details here shown for illustrative purposes, except as I may be limited by the 100 hereto appended claims, knowing that changes can be made therein without departing from the spirit of the invention.

I claim,—

1. A bubbling cup comprising a globular-shaped body having a concaved top with a discharge opening therein, one or more non-squirt tubes from said concaved top through

- the body of said cup, means for attaching said cup to a source of water supply, with one or more inlet openings or ports into the interior of said cup, and an imperforate deflector member therein directly over said inlet openings, or ports, and against which inflowing water is discharged, whereby to make it necessary for said cup to be filled before water is discharged from the discharge opening in said concaved top.
2. A bubbling drinking cup of the character shown and described, comprising a body of globular form having a concaved top with central discharge opening therein, and adapted at its other end to be attached to a source of water supply, with one or more inlet ports into the interior of said cup, an imperforate deflector adjustably mounted within said cup directly over said inlet ports and in alinement with said central discharge opening in said concaved top, said deflector being adapted at its upper end to be engaged by an instrument inserted through said central discharge opening for adjusting said deflector, and one or more non-squirt tubes from said concaved top through the body of said cup, whereby to provide a way of escape for the water when the hand is placed over the top of said cup.
3. A bubbling drinking cup of the character shown and described comprising a body

of globular form having a shallow concaved top with a central discharge opening therein, one or more non-squirt tubes extending through the body of said cup and communicating at their upper ends with the concaved surface thereof and at their lower ends discharging through the outside wall of the cup, said cup being adapted at its lower end to be connected with a source of water supply, with inlet supply openings to the inside of said cup, and an imperforate buffer-like deflector member adjustably disposed within said cup directly above the inlet openings into the interior thereof, whereby the water discharged into the interior of said cup strikes said deflector, whereby the interior of the cup must be filled before water can be forced from the central discharge opening thereof, said deflector member being adapted at its lower end to cut off the supply of water to the interior of said cup, and being accessible only by means of an instrument through said central opening in said concaved top, substantially as described.

Signed at Portland, Oregon, this 8 day of January, 1915.

MARTIN L. RAHNER.
